CARBONATING DEVICE

Frederick H. Tweed, Chicago, Ill., assignor to
The Dole Valve Company, Chicago, Ill., a cor-
poration of Illinois

Application July 25, 1934, Serial No. 736,826

7 Claims. (Cl. 261—19)

This invention relates to carbonating devices for producing carbonated liquids, and has for its object to provide a new and improved device of this description. The invention has as a further object to provide a carbonating device which insures pure and highly carbonated liquid free from atmospheric air at all times. The invention has as a further object to provide a carbonating device which is simple in operation, compact in construction and automatic in its performance. The invention has as a further object to provide a carbonating device which eliminates cumbersome, noisy and expensive agitating devices. The invention has as a further object to provide a carbonating device for automatically discharging from the carbonating receptacle atmospheric air which would otherwise accumulate therein.

In carbonating liquids, for example, there is atmospheric air contained in the liquids and this atmospheric air, in the old carbonating device, accumulates in the carbonating receptacle and such air injures the carbonated water and causes it to taste flat and insipid, thus reducing its acceptability to the user. This atmosphere, even in small quantities, may render the carbonated water unfit for a beverage. This atmospheric air also gives annoyance by causing a spurting of the liquid when discharged from the dispensing device, this violent action of the air and the liquid even tending to knock the glass out of the hand of the operator. One of the objects of the present invention is to prevent this and provide a carbonating device free from these evils.

The invention has further objects which are more particularly pointed out in the accompanying description.

Referring now to the drawings, Fig. 1 is a side view of one form of carbonating device showing the electric pump, motor and switch associated therewith;

Fig. 2 is a sectional view through the carbonating receptacle;

Fig. 3 is a plan view of the carbonating receptacle.

Like numerals refer to like parts throughout the several figures.

Referring now to the drawings, I have shown a carbonating receptacle 1 which is supplied with liquid by any suitable means. In order to show a complete assembly I have illustrated an electric pump 2 as supplying the liquid, said pump operated by the electric motor 3 connected by the conductors 3a with any suitable source of supply and controlled by the automatic pressure switch 4. The pump draws the liquid through the pipe 5

from the source of supply and discharges it through the pipe 6 and the coupling member 7 into the carbonating receptacle 1. The carbon dioxide gas passes through the pipe 8 which is connected to the source of supply. This pipe 8 is connected to the fitting 9 which is connected with the carbonating receptacle 1 by means of a plug 10. The fitting 9 has a passageway 11 controlled by a valve 12 in a chamber 13. A fitting 14 has a passageway 15 which communicates with the chamber 13, and a pipe 16 is connected with said fitting and conducts the carbon dioxide gas to the bottom of the carbonating receptacle and discharges it therein at the point 17.

Some means for distributing the gas is provided, such as the perforated plate or diaphragm 18. The valve 12 is connected with a valve stem 19 and has a shoulder 20. A spring 21 is located between this shoulder and the bottom of the chamber 13. The valve stem 19 is connected to 20 the sliding member 22 which forms a control member for said valve, the valve being controlled by the liquid entering through the fitting 7. Associated with the sliding member 22 is a hollow perforated sliding member 23 and a spring 24. 25 The sliding member 22 and the hollow sliding member or piston 23 are provided with perforations 25 and 25a in alignment but out of registration, except as hereinafter set forth. The piston 23 is pressed upwardly by the spring 24 and its movement is stopped by the pin 23c. When the liquid enters the fitting 7 it enters in pulsations from the pump, and each pulsating charge of liquid moves the member 22 down so as to open the valve 12 and permit the gas to pass into the 35 carbonating receptacle. The movement of the member 23 due to the pulsating pressure also permits the liquid to pass into the carbonating receptacle, the downward movement of the sliding member causing openings 25 and 25a in the two 40 sliding members to register so that the water can pass readily through them into the carbonating receptacle. The springs at the ends of the pulsations move the parts back to their original position and close the valve 12.

It will thus be seen that by means of this arrangement the carbon dioxide gas is admitted to the carbonating receptacle in synchronism with the water supply under pressure forced therein by the water supply pump, and the parts are arranged so as to admit the gas in the right proportions and in the pulsating form as the water pulsates from the discharge of the supply pump. Under such conditions the absorption of the carbon dioxide gas by the liquid in the receptacle 55

becomes almost instantaneous, provided that the carbon dioxide gas, entering at the bottom of the carbonating receptacle, is broken up into small portions or bubbles, as by means of the perforated plate 18. It will further be seen that the water forced into the carbonating receptacle must be forced in under a continually increased rise of pressure in the carbonating receptacle, and this increased pressure also assists in securing the proper absorption of the carbon dioxide by the liquid.

I also provide means for admitting additional carbon dioxide gas to the carbonating receptacle in response to the raising of the level of the liquid therein. For this purpose a pipe 26 is connected with the fitting 9 and leads to the pipe 16 through a valve which is controlled by the height of the liquid in the carbonating receptacle. In this construction the pipe 26 is connected with a fitting 27 having a passageway 28 which communicates with a chamber 29. A valve 30 controls this passageway. Another passageway 31 in the fitting communicates with the chamber 29 and connects with the pipe 26a leading to the pipe 16. The valve 30 is provided with a stem 32. The valve is pressed toward its open position by a spring 33 and toward its closed position by a lever 34 pivoted at 35, and provided with a portion 36 which engages the valve stem 32. Connected with the lever is a float 37 which floats in the liquid. When the liquid lowers to a certain level the float drops and the lever 34 presses the valve stem 32 and closes the connection between the pipes 26 and 26a, shutting off this flow of the gas. As the liquid rises above a predetermined point the float rises so as to lift the lever and release the stem 32 so that the spring 33 opens the valve and permits gas to pass from the pipe 26 into the pipe 26a, and thence the pipe 16 and thence into the carbonating receptacle.

Some means is provided for automatically discharging the air or mixed air and carbon dioxide gas which rises to the top of the carbonating receptacle. For this purpose I provide a passageway 38 which leads from the interior of the carbonating receptacle to the exterior thereof. The valve 39 controls this passageway. This valve is controlled by a lever 40 which is pivoted at 41 and which is connected with a float 42. When the liquid in the receptacle falls below a predetermined point the float moves the lever 40 so as to open the valve 39 and permit the air or mixed air and carbon dioxide gas to escape from the receptacle. This is a very important factor in the dispensing of carbonating liquids, as it prevents the liquid from becoming flat or insipid due to the action of the air.

When the water from the pump enters the sleeves 22 and 23 a pressure is built up in said sleeves equal to the pressure produced by the pump, and this moves the hollow sleeve or piston 23 downwardly compressing the spring, and causes the openings 25 and 26a to register so that the water gradually passes out into the receptacle. When this water enters the sleeve 23 the pressure causes the sleeve to be moved downwardly so as to open the valve 12 and this pressure being built up in this sleeve holds the valve open after the pump pressure has decreased. When, however, the water leaks out through the openings 25 and 26a, the pressure ceases and the valve 12 is closed. It will thus be seen there is an intermittent opening and closing of this valve 12 to let the gas in the receptacle, and

that the valve is held open by the pressure built up in the sleeve 23.

The use and operation of my invention are as follows.

When the device is in operation, the pipe 8 is connected to a source of supply of carbon dioxide gas and the pipe 6 is connected with the source of supply of the liquid and the electric motor 3 is connected in circuit. The liquid is then drawn from the source of supply and discharged through the pipe 6 and the coupling member 7 into the receptacle 1. The discharge of the carbon dioxide gas through the pipe 8 into the pipe 16 and thence into the receptacle is controlled by the valve 12 attached to the sliding member 22. The pump causes a pulsating movement of the liquid through the coupling member 7 and when this liquid enters the sliding member 22, it causes it to move downwardly and open the valve 12 and carbon dioxide gas then passes from the pipe 8 into the pipe 16 and thence into the bottom of the receptacle 1. This liquid then moves the hollow perforated sliding member 23 downwardly until the openings 25 register with the openings 25a in the hollow sliding member 22, and then the liquid passes out into the receptacle 1 and the spring 21 moves the valve 12 to its closed position and the spring 24 moves the hollow perforated member 23 up against the pin 23c so as to shut off the flow of the liquid into the receptacle 1. The carbon dioxide gas passes into the receptacle at the bottom below the member 18 and is by this member 18 finely divided so as to be thoroughly commingled with the water.

At the next pulsation of the pump, the operation above described is repeated. When the liquid in receptacle 1 reaches such a height that it lifts the float 37, the spring 33 then moves the valve 30 and the carbon dioxide gas passes from pipe 26 through passageways 28 and 31 into pipe 26a, and thence into pipe 16, and thence into the bottom of the receptacle 1, this being a continuous process made desirable by the height of liquid in the receptacle 1. When a sufficient amount of the liquid is properly carbonated, it is drawn off and the operation then repeated. When the liquid is drawn off so that the level is such as to lower the float 42 to open the valve 39, the mixed gas and air is discharged through the pipe 38 into the outside atmosphere.

I claim:

1. A carbonating device comprising a receptacle having a single chamber therein, a liquid inlet at the top thereof connected with a pump that pumps liquid into the receptacle and a gas inlet at the bottom thereof, the liquid and gas inlets discharging into said single chamber, a control valve for the gas at the top of said receptacle in proximity to the liquid inlet, said control valve actuated by the pulsations of the liquid due to the pump.

2. A carbonating device comprising a receptacle, a liquid inlet at the top thereof connected with a pump that pumps liquid into the receptacle and a gas inlet at the bottom thereof, a control valve for the gas inlet, said control valve located at the top of said receptacle in proximity to the liquid inlet, a movable member in the liquid inlet moved by the pulsations of the entering liquid due to the pump, a connection between said movable member and said control valve for the gas whereby the gas is intermittently admitted to the receptacle.

3. A carbonating device comprising a recepta-

- cle, a liquid inlet and a gas inlet, a control valve in the gas inlet on the exterior of said tank and in proximity to the liquid inlet, a movable part in the liquid inlet connected with the gas control valve, a spring associated therewith normally holding the gas control valve closed, the liquid entering the liquid inlet moving said movable device against the action of said spring to open the gas control valve.
- 10 4. A carbonating device comprising a receptacle, a liquid inlet and a gas inlet, a control valve in the gas inlet in proximity to the liquid inlet, a movable part in the liquid inlet connected with the gas control valve, a spring associated therewith normally holding the gas control valve closed, the liquid entering the liquid inlet moving said movable device against the action of said spring to open the gas control valve, and means for intermittently varying the pressure of the liquid entering the liquid inlet so as to intermittently open and close the gas control valve.
- 15 5. A carbonating device comprising a receptacle, a liquid inlet and a gas inlet for said receptacle, valves for controlling said liquid and gas inlets, the valve for the liquid inlet being connected with the valve for the gas inlet so that the gas inlet is automatically controlled by the liquid passing in through the liquid inlet, and means for automatically admitting gas into said receptacle in response to an excessive rise in the liquid level in the receptacle, whereby the proper proportion of liquid and gas is maintained.
- 20 6. A carbonating device comprising a receptacle, a liquid inlet and a gas inlet for said receptacle, valves for controlling said liquid and gas inlets, the valve for the liquid inlet being connected with the valve for the gas inlet so that the gas inlet is automatically controlled by the liquid passing in through the liquid inlet, and means for automatically admitting gas into said receptacle in response to an excessive rise in the liquid level in the receptacle, whereby the proper proportion of liquid and gas is maintained.
- 25 7. A carbonating device comprising a receptacle, a liquid inlet and a gas inlet, a control valve in the gas inlet in proximity to the liquid inlet, a movable cylinder associated with said liquid inlet and into which the liquid passes a connecting device which connects said movable cylinder with said gas control valve, a piston in said cylinder, a spring beneath said piston, and a series of openings in the cylinder building up a pressure therein so as to move it to open the gas control valve and hold it open, the movement of the piston uncovering said openings letting the water gradually escape so as to decrease the pressure and permit the spring associated with the gas control valve to close it.
- 30
